WELDED GRATING

William C. Heath, Shorewood, Wis., assignor to
 A. O. Smith Corporation, Milwaukee, Wis., a
 corporation of New York

Application March 27, 1941, Serial No. 385,478

2 Claims. (Cl. 189—82)

This invention relates to welded grating and has been applied to the construction of grating for use in safety walks and the like.

The principal object of the invention is to provide a welded grating made up of parallel bars held in spaced relation by a set of parallel cross bars integrally secured thereto, and which grating is considerably stronger and less costly than the mechanically interlocked type of grating heretofore used.

One embodiment of the invention is illustrated in the accompanying drawing in which:

Figure 1 is a perspective view of a grating with parts broken away;

Fig. 2 is a perspective view of a longitudinal bar for the grating; and

Fig. 3 is a perspective view of a cross bar for the grating.

The grating comprises a series of spaced parallel longitudinal bars 1 and a series of spaced parallel cross bars 2.

The bars 1 and 2 are constructed of sheet metal strips disposed on edge in the same general plane to present a common safety tread on top of the structure. The cross bars 2 are preferably disposed at right angles to the longitudinal bars 1, although they may be disposed at an acute angle if desired. When the bars are disposed at right angles it is easy to construct rectangular sections of tread having convenient dimensions for use as walks and the like.

The bars 1 and 2 are preferably sheared in pairs from a single continuous strip of metal. In this construction, the serrated upper edges are provided in the shearing operation and two bars are formed simultaneously without waste of metal from shearing.

The longitudinal bars 1 have vertical slots 3 cut downwardly from their upper edges and spaced longitudinally of the bars a distance equal to the spacing of the cross bars 2 to receive the latter. The slots 3 are slightly wider than the thickness of the cross bars for ease of assembly, any crevice due to the clearance usually being filled later with galvanizing.

The grating is preferably constructed with the intermediate cross bars 2 of less depth than the longitudinal bars and with both bars slotted. In such construction the cross bars 2 preferably are of greater depth than the slots 3, and have their lower edges slotted as at 4 to receive the bars 1.

The end cross bars 5 are of the same depth as the longitudinal bars 1 and the lower edges of the bars 5 have slots 6 cut therein to receive the longitudinal bars 1 at the crossings of the respec-

tive bars. In this construction, the slots 4 and 6 will each be approximately one-half of the total depth of the respective cross bars, although any suitable ratio of depths may be employed.

The spacing of the cross bars longitudinally of the structure will normally be greater than the distance between the longitudinal bars, since this provides a structure of sufficient strength and of good appearance.

10 In manufacturing the grating, after the respective bars are formed with their serrated edges, as previously referred to, they are stacked and the respective slots 3, 4 and 6 milled in a group of them simultaneously. From there the bars pass to the assembly station where they are assembled into the grate, either by hand or by an automatic machine.

15 After assembly, the grate passes through the welding machine where an electrode is applied in contact with the upper edge of each cross bar 2 and an opposite electrode is applied in contact with the lower edges of the longitudinal bars 1. A very light resistance welding current and light pressure is thereby applied across the contacting surfaces at the bottoms of the slots 3, 4 and 6. No attempt is made to weld the parts at the sides of the slots and it has been found that a 20 grating of fully sufficient strength can be obtained without substantial mushing of the parts together in welding causing extrusion of metal from the slots. By welding in a plane intermediate the upper and lower edges of the respective bars, all parts are enabled to carry their respective loads and stresses with greater freedom from eccentricity. The slotting of both longitudinal and cross bars provides an interlocked structure of great stiffness.

25 25 The grating passes through the welding machine where an electrode is applied in contact with the upper edge of each cross bar 2 and an opposite electrode is applied in contact with the lower edges of the longitudinal bars 1. A very light resistance welding current and light pressure is thereby applied across the contacting surfaces at the bottoms of the slots 3, 4 and 6. No attempt is made to weld the parts at the sides of the slots and it has been found that a 30 grating of fully sufficient strength can be obtained without substantial mushing of the parts together in welding causing extrusion of metal from the slots. By welding in a plane intermediate the upper and lower edges of the respective bars, all parts are enabled to carry their respective loads and stresses with greater freedom from eccentricity. The slotting of both longitudinal and cross bars provides an interlocked structure of great stiffness.

35 Following the welding operation the grating is usually pickled and then galvanized or otherwise 35 suitably coated. The galvanizing tends to fill the crevices at the side walls of the slots and provides a more rigid structure, as well as protecting the steel from rust.

40 The method of making the grating is claimed in Patent No. 2,335,181, filed April 30, 1942, issued November 23, 1943.

45 The invention may have various embodiments within the scope of the accompanying claims.

I claim:

50 50 1. A welded grating comprising a series of laterally spaced parallel longitudinal bars of strip metal vertically disposed on edge with their upper edge surfaces lying in substantially the same horizontal plane to provide a common tread, a series of spaced parallel cross bars of strip metal

similarly disposed on edge with their upper surfaces lying in the general plane of said tread surface, said cross bars being disposed loosely in regularly spaced slots with vertical side walls extending downwardly from the upper edges of said longitudinal bars, and welds joining the bars only at the flat bottom of the respective slots near the mid-plane of the structure and without extrusion of metal from the slots.

2. A welded grating comprising a series of laterally spaced parallel longitudinal bars of strip metal vertically disposed on edge with their upper edge surfaces lying in substantially the same horizontal plane to provide a common tread, a series of spaced parallel cross bars of strip metal 15

similarly disposed on edge with their upper surfaces lying in the general plane of said tread surface, said cross bars being disposed loosely in regularly spaced slots with vertical side walls extending downwardly from the upper edges of said longitudinal bars, welds joining the bars only at the flat bottom of the respective slots near the mid-plane of the structure and without extrusion of metal from the slots, and galvanizing material in the interstices between the vertical side walls of said slots and the respective bars disposed in said slots to provide a rigid structure.

WILLIAM C. HEATH.
